CASEMENT WINDOW OPERATING MEANS

Filed April 30, 1936

UNITED STATES PATENT OFFICE

2,072,083

CASEMENT WINDOW OPERATING MEANS

Harry E. Campbell, Baltimore, Md., assignor to
 Campbell Metal Window Corporation, New
 York, N. Y., a corporation of Maryland

Application April 30, 1936, Serial No. 77,114

13 Claims. (Cl. 268—117)

The general object of the present invention is to provide improved means for adjusting a casement window into, and maintaining it in different positions.

5 A more specific object of the present invention is to provide a casement window arrangement in which the window sash is biased for movement from its fully closed position into its wide open position, and may be adjusted into, and 10 held in, different open positions, and may be locked in its closed position, by manual adjustments given the inner end portion of a flexible operating element connected at one end to the sash and extending from the latter to the inner 15 side of the casing, and cooperating with means carried by the casing, and including parts through which the said adjustments of said element lock the sash to, or unlock it from the casing, when the sash is in its closed position, and, 20 when the sash is in an open position, cause said element to be either gripped at one or another point along its length or released, and thereby hold the sash in one or another open position, or permit opening and closing movements of the 25 sash.

In a preferred embodiment of the invention, the sash is given its bias for opening movement by spring hinge connections between the sash and the window casing, and the flexible operating connection through the window sash is a light pull chain, and the cooperating means carried by the casing includes a member which is pivoted to the casing and is formed with a guide passage for the flexible element, 35 and is adapted to be given pivotal movements by lateral adjustments of the portion of the element at the inner end of said guide passage. The said pivoted member is provided with a locking hook moved by the pivotal movements of 40 said member into and out of locking engagement with the sash when the latter is in its closed position. In the specific form of the invention illustrated and described, in detail herein, when the sash is out of its fully closed position, pivotal movements of the said pivoted member move said element into and out of engagement with the stationary walls of a slot which is adapted to receive a link of the chain but is too narrow to permit longitudinal movement of the chain through the slot.

50 The various features of novelty which characterize my invention are pointed out with particularity in the claims annexed to and forming a part of this specification. For a better understanding of the invention, however, its advan-

tages and specific objects attained with its use, reference should be had to the accompanying drawing and descriptive matter in which I have illustrated and described preferred embodiments of the invention. 5

Of the drawing:

Fig. 1 is an elevation of a casement window construction as seen from its inner side;

Fig. 2 is a horizontal section on the broken line 2—2 of Fig. 1; 10

Fig. 3 is a partial section on the line 3—3 of Fig. 1;

Fig. 4 is a perspective view of a chain guiding and holding and window locking element of the construction shown in Figs. 1, 2 and 3; 15

Fig. 5 is a fragmentary elevation of a portion of the window casing and sash construction shown in Fig. 1, and taken at right angles to that figure;

Fig. 6 is a partial section on the line 6—6 of Fig. 3; and 20

Fig. 7 is a side elevation of a portion of a modified form of the element shown in Fig. 4.

The window construction shown in the drawing comprises a metallic window casing element 25 1 adapted for inclusion in a building wall, and in the form of a rectangular frame surrounding a rectangular window opening adapted to be closed by a metallic window sash member 2, which is hinge connected to the casing frame 1 at one 30 side of the latter. As shown in Fig. 2, the casing frame is of Z bar cross section, comprising inner and outer parallel flange or rib portions 3 and 4 connected by a transverse web portion 5. The sash 2 comprises a marginal frame portion of 35 similar cross section, and in the closed position of the sash, its inner and outer frame flanges 6 and 7 abut against the casing flanges 3 and 4 respectively, with the transverse sash web 8 alongside and spaced some distance away from the casing web portion 4. As shown, the sash 40 comprises central vertical and horizontal bar portions 9 and 10, respectively, which in conjunction with the sash frame, provides seats for four glass panes 11. The latter may be anchored 45 against their seats in any usual or suitable manner which need not be illustrated or described herein, as the invention is not concerned with the mounting of the window panes, or with the shape or number of the latter. 50

The window sash 2 is hinged at one side to the corresponding side of the window casing by upper and lower hinge connections, each shown as comprising a bracket 12 welded or otherwise attached 55 to, and projecting outwardly from, the outer

flange 4 of the casing, a generally similar bracket part 13 welded or otherwise attached to the outer flange 7 of the window casing, and a bolt or analogous connection 14 between the two brackets 5 and serving as a hinge pintle. Each hinge connection includes a spring 15 shown as comprising a body portion of spring wire coiled about the hinge pintle, and tangential end extensions 16 and 17. The extension 16 passes through an 10 opening formed for the purpose in a lug or projection 18 from the adjacent side of the corresponding bracket 12. The other spring end extension 17 lies in the corner space at the adjacent side of the bracket 13 and in front of a vertically 15 extending flange portion 19 of the bracket part 13. The spring 15 is under tension tending to spread its end portions 16 and 17 apart, and thereby subjects the sash to a constantly acting spring opening force.

20 The flexible window operating element 20 used in accordance with the present invention includes suitably short sections which can move laterally into the narrow portion of a keyhole slot alternating with sections which are not longitudinally 25 movable through said slot portion but which as well as the first mentioned sections are longitudinally movable through the large diameter portion of the slot. Preferably, the element 20 is a chain, and, ordinarily and as shown, is formed with sheet 30 metal links. As shown, the chain 20 is connected to the sash at the free edge of the latter and about midway between the top and bottom of the sash, by means of a hook or eye part 21, having a threaded stem passing through the sash flange 6, 35 and held in place by a nut 21 bearing against the outer side of the flange.

As shown, the chain 20 extends through, and is longitudinally movable in the upper portion of a vertically elongated opening 22, formed in the 40 casing flange 3, the attachment part 21 being in register with the upper portion of the opening 22 when the sash is in its closed position. The chain 20 also extends through an opening formed in a metallic part 25 secured to the window casing 45 flange 3, at the front or room side of the latter, of keyhole form, the last mentioned opening comprising a rounded upper portion 23 large enough for the free longitudinal movement of the chain 20, and an elongated lower portion 24, which is 50 wide enough to receive the shank or body portions of the chain links but is too narrow for the longitudinal movement of the enlarged ends of the chain links, as is plainly shown in Fig. 6. As shown, the part 25 comprises a bar-like body portion 55 formed adjacent its ends with holes 26 for securing bolts passing through those holes and threaded into the casing flange 3. At its front side, the member 25 is formed with lugs or ears 27, serving as hinge brackets or ears, apertured 60 to receive the ends of a pivot pin 28 on which is journaled a lever member 29. The latter comprises a flat blade portion or locking part 30 through which the pivot pin 28 extends and which is received between the ears 27, and extends 65 through the keyhole opening portion 24, and opening 22. As shown, a portion of the member 29, in front of the part 25, is thicker than the blade portion 30 and comprises curved shoulders 31 in abutting relation with the rounded edges of 70 the hinge ears 27, and also comprises a tubular portion 32, extending transversely to the general direction of the blade portion 30. The bore or passage 33 through the lever portion 32 is of a diameter to permit free longitudinal movement 75 therethrough of the chain 20.

At its rear end, the blade portion 30 of the lever element, is provided with a lateral projection 34. The latter, in the locked condition of the window 5 engages the rear side of a locking lug or projection 35, which is rigidly secured to the sash, and, as shown, is a projection from a bar-like part 37 screw connected to the sash web portion 8. In effect the blade 30 and its projection 34 form a sash locking hook portion of the member 29. The engaging surfaces of the cooperating locking parts 10 of 34 and 35 are rounded and shaped to conjointly provide a camming, or wedging, action by which the sash flanges 6 and 7 are pressed snugly against the casing flanges 3 and 4, respectively, when the sash is locked in its closed position. In that condition, the shank of one of the chain links is received in the portion 24 of the keyhole opening.

To move the sash out of its fully closed and locked position, the lever member 29 is turned in the direction to move its portion 32 out of the depending position of the latter, shown in Fig. 4 and in full lines in Fig. 3, and into the dotted line position shown in Fig. 3. This moves the cam locking part 34 of the lever out of engagement with the sash carried locking part 35, and moves the portion of the chain 20 previously received in the narrow portion 24 of the keyhole opening through the part 25, into the enlarged rounded upper portion 23 of that slot. With the lever 29 in position shown in dotted lines in Fig. 3, the sash is free to move in the opening direction under the action of its spring hinges, unless and except as such movement is prevented or reversed by force transmitted to the sash through the chain 20.

The sash may be secured in any open position into which it is moved as a result of the opposing actions of the spring hinges and the pull on the chain 20, by turning the lever element 29 from its dotted line position into its full line position 40 shown in Fig. 3. When the lever element is so turned into its full line position, the chain is moved laterally or downward out of the larger upper portion 23 into the narrowed lower portion 45 24 of the keyhole opening in the member 25. The window sash may thus be secured in any open position in which one or another of the chain links has its shank or body portion received in the portion 24 of the key-hole slot.

The projection 36 from the part 25 is adapted 50 for use in latching in place a window screen, not shown, and forms no part of the invention claimed herein. As shown, the lever member 29 is provided with a projection 38 engaging the member 35 and preventing over-movement of the lever member when the latter is turned from its dotted line position into its full line position of Fig. 3. In the normal position of the lever 29 shown in Fig. 4, the projection 38 closes the lower end of the slot portion 24 in the member 25, as 60 is especially desirable because of the lateral enlargement 24^x of said slot portion at one side provided to accommodate the movement of the lever locking part 35 between its full and dotted line positions shown in Fig. 3, and in the assembly of the parts 25 and 29. As shown, also, the member 25 is formed with a recess 39 at its side adjacent the flange 6, which slidingly receives a bar-like part 40. The latter is gravitationally held in engagement with the chain 20 and closes 70 the upper portion of the slot 22 when the lever member 29 is in its position shown in full lines in Fig. 3.

As will be apparent to those skilled in the art, the sash locking and adjusting means shown are 75

compact, simple in construction, positive in action, and easily operated. All necessary operative actions may be effected by forces applied by the hand of the operator to the portion of the 5 chain projecting into the room through the passage 33 in the lever member 29, since the lever member 29 may be readily turned between its full line and dotted line positions shown in Fig. 3, by force applied to the free end of the chain 10 in the direction to bodily rotate the portion of the chain within the passage 33 about the axis of the pivot pin 28. By such lateral movements of the chain the latter is caused to engage and disengage the means provided to engage and hold 15 the chain against longitudinal movement when the window is to be held in its different open positions, said means, in the form shown, consisting of the portions of the part 25 which form the side walls of the portion 24 of the opening 20 through the part 25.

Those skilled in the art will appreciate the advantages in construction simplicity, ease of operation, obtained by the single simple pivoted member, such as the lever 29, to positively lock 25 the sash in its closed position, and to guide the chain element 20 in its longitudinal and lateral movements, and which may be given all necessary movements by forces applied to it through the operating chain element.

30 In Fig. 7, I have illustrated a modification of the construction shown in Fig. 4. The modification shown in Fig. 7 includes parts 23^a, 24^a, 25^a, 26^a, 27^a, 28^a, 29^a, 30^a, 31^a, 32^a, 33^a and 40^a, corresponding respectively to the parts 23 to 33, and 35 40, of the construction. The lever 29^a differs, mainly from the lever 29, only in the shape of its shoulders 31^a, and in the form of its locking part 34^a; the latter, instead of being a lateral projection from the blade portion 30^a of the lever, is a hook end extension of the blade portion lying between the planes of the sides of said 45 portion. The sash carried locking projection 35^a is elongated for engagement, as shown in Fig. 7, by the hook extension 34^a. With the locking part arrangement shown in Fig. 7, the slot portion 24 in the member 25^a need be no wider than is required by the thickness of the blade portion 30^a, and is filled by the latter in the position of 50 the parts shown in Fig. 7 so that the covering function of the part 38 shown in Fig. 4 is not required, and the lever 29 includes no part like the part 38. Excess movement in the locking direction of the lever is prevented in the construction shown in Fig. 7, by the special shape given to 55 the lever shoulders 31^a, and the edges of the ears 27^a engaged by those shoulders, when the parts are in the positions shown in Fig. 7. The lower portions of the shoulders 31^a are flat, as are corresponding portions 27^b of the edges of the ears 27^a engaged by the flat portions of the shoulders 31^a.

As shown, the outer face of the part 25^a immediately below the rounded portion 23^a of its key-hole slot, is recessed or indented at 27^c to receive 60 the rounded end of the chain link engaged by the edges of the slot portion 24^a when the sash is locked in an open or partly open position. The notches 27^c facilitate the locking of the chain element against longitudinal movement and may 65 be provided in the construction of Fig. 4, as in that of Fig. 7.

The construction of Fig. 7 has certain practical advantages over that shown in Fig. 4, particularly in that the lever 27^a is easier to make than 70 the lever 27, though each form of lever may be

cast and requires little machining. It is advantageous also that the lower end of the slot portion 24^a need not be laterally enlarged, as the slot portion 24 of Fig. 4 is enlarged for the passage of the lateral locking projection 34.

5 While in accordance with the provision of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features. 10 15

Having now described my invention, what I claim as new and desire to secure by Letters Patent, is:

1. In a casement window, a window casing, a window sash hinged to said casing to turn between open and closed positions, means tending to turn said sash away from, and opposing its return to its closed position, a flexible window operating element connected at one end to said sash and extending therefrom to the inner side 25 of the window, sash locking means mounted on said casing and rendered operative and inoperative by movements of a portion of said element at the inner side of the window in directions transverse to the length of said portion and 30 adapted, when rendered operative, to provide a locking connection between said casing and sash which is independent of said element, and means mounted on said casing for holding said element against longitudinal movement and adapted to be 35 rendered operative and inoperative by said transverse movements of said element portion.

2. In a casement window, a window casing, a window sash hinged to said casing to turn between open and closed positions, means tending to turn said sash away from, and opposing its return to its closed position, a flexible window operating element connected at one end to said sash and extending therefrom to the inner side 40 of the window, a sash locking member pivotally mounted on said casing and comprising a guide passage through which said element extends and adapted to be moved between sash locking and unlocking positions by movements of the portion of said element extending away from said passage 45 at the inner side of said window in directions transverse to the length of said portion, and means actuated by said transverse movements of said portion to hold said element against, or release it to permit longitudinal movement of the 50 element.

3. In a casement window, a window casing, a window sash hinged to said casing to turn between open and closed positions, means tending to turn said sash away from, and opposing its return to its closed position, a flexible window operating element connected at one end to said sash and extending therefrom to the inner side of the window, a sash locking member pivotally mounted on said casing and comprising a portion including a guide passage through which said element extends and adapted to be moved between sash locking and unlocking positions by movements of the portion of said element extending away from said passage at the inner side 60 of said window in directions transverse to the length of said portion, and casing carried means between said member and said sash portion adapted when in operative engagement with said element to hold the latter against longitudinal 65 70 75

movement, and said element being adapted to be brought into and out of operative engagement with said means by the said transverse movements of said element portion.

5. 4. In a casement window, a window casing, a window sash carrying a locking part and hinged to said casing to swing relatively thereto between its open and closed positions, means tending to move the window sash away from and opposing its return to its closed position, a flexible window operating element connected at one end to said sash, a member pivotally mounted on the casing and formed with a guide passage for said element and with a locking part and adapted to be given said pivotal movements by lateral movements of the portion of said element extending away from the end of said passage remote from said sash, and means adapted to be rendered operative and inoperative to hold said element against longitudinal movement by the said lateral movements of said element portion.

5. In a casement window, a window casing, a window sash carrying a locking part and hinged to said casing to swing relatively thereto between its open and closed position, means tending to move the window sash away from and opposing its return to its closed position, a flexible window operating element connected at one end to said sash, element holding means carried by said casing, and a member pivotally mounted on the casing and formed with a guide passage for said element and with a locking part and adapted by its pivotal movements to move said element into and out of engagement with said holding means and, when said sash is in its closed position, to move its locking part into and out of operative engagement with the first mentioned locking part.

6. In a casement window, a window casing, a window sash carrying a locking part and hinged to said casing to swing relatively thereto between its open and closed positions, means tending to move the window sash away from and opposing its return to its closed position, a flexible window operating element connected at one end to said sash, element holding means carried by said casing, and a member pivotally mounted on the casing and formed with a guide passage for said element and with a locking part and adapted by its pivotal movements to move said element into and out of engagement with said holding means and, when said sash is in its closed position, to move its locking part into and out of operative engagement with the first mentioned locking part, and adapted to be given said pivotal movements by lateral movements of the portion of said element extending away from the end of said passage remote from said sash.

7. In a casement window, a window casing, a sash carrying a locking part and hinged to said casing to swing relative thereto between open and closed positions, means tending to swing the sash away from, and opposing its return to its closed position, a flexible element connecting at one end to said sash and extending therefrom to the inner side of the window, and element guiding means, a movable locking part, and element holding means carried by said casing, said guiding means permitting free longitudinal movement of said element but restricting transverse movement of the portion of said element immediately adjacent said casing to a range between two predetermined positions of said portion and said movable locking part being moved into and out of operating engagement with the first mentioned

locking part, when said sash is in its closed position, by movement of said element portion between said two positions and said element holding means being rendered operative or inoperative to hold said element against longitudinal movement, when said sash is out of said closed position, by movements of said element portion between said two positions.

8. In a casement window, a window casing structure provided with an opening comprising portions of different widths, a window sash, spring hinges connecting said sash to said casing structure and tending to move said sash to an open position, a flexible element connected at one end to said sash at a point thereof which is adjacent said opening when the sash is in its closed position, and extending through said opening and longitudinally movable through a wider portion of said opening and laterally movable into and out of a narrower portion of said opening and held against longitudinal movement when in the last mentioned portion by engagement with the walls thereof, and a lever mounted on said casing structure for angular movement into and out of locking engagement with the sash, when the latter is in its closed position, and by said movements moving said element between said narrower and wider portions of said opening.

9. In a casement window, a window casing formed with a keyhole opening, a member rigidly attached thereto and formed with an opening in register with the first mentioned opening, a window sash, a spring hinge connection between said sash and casing at a side of the latter remote from said opening and tending to move said sash to an open position, a flexible element connected at one end to said sash at a point thereof adjacent said openings when the sash is in its closed position and extending through said openings and longitudinally movable through a wider portion of the first mentioned opening and laterally movable between said portion and a narrower portion of the first mentioned opening and held against longitudinal movement when in said narrower opening portion by the walls thereof, and a lever pivotally mounted on said member for movement into and out of locking engagement with said sash and holding said element in said narrower or wider opening portions accordingly as said lever is in one angular position or another.

10. In a casement window, a window casing formed with an opening, a window sash hinged to said casing at a side thereof remote from said opening to turn between open and closed position, means tending to turn said sash away from and opposing its return to its closed position, a flexible window operating element connected at one end to said sash and extending therefrom to the inner side of said window through said opening, a part detachably secured to said casing, a lever member pivotally mounted on said part and comprising a sash locking hook portion extending through said opening and provided with an element guideway at the inner side of the window which extends transversely to the axis of the pivotal mounting of said lever and being adapted to be turned into and out of locking engagement with the sash, when the latter is in its closed position, by lateral movements given the portion of said element extending away from said guideway at the inner side of the window, and means adapted to be rendered operative or inoperative by the said lateral movements for holding said element against longitudinal movements.

11. In a casement window, a window casing

- formed with an opening, a window sash hinged to said casing at a side thereof remote from said opening to turn between open and closed position, means tending to turn said sash away from and 5 opposing its return to its closed position, a flexible window operating element connected at one end to said sash and extending therefrom to the inner side of said window through said opening, a part detachably secured to said casing and 10 formed with a keyhole slot opening comprising an elongated lower portion and an enlarged upper portion, a lever member pivotally mounted on said part and comprising a blade like portion terminating at its end in a sash locking hook, said 15 blade-like portion extending through said lower portion of said keyhole slot opening and through said casing opening, said lever member being provided with an element guideway at the inner side of the window, which extends transversely to the axis of the pivotal mounting of said lever, and said lever member being adapted to be turned into and out of the position in which said hook 20 is in locking engagement with the sash, when the latter is in its closed position, by lateral movements given the portion of said element extending away from said guideway at the inner side of the window, and means adapted to be rendered operative or inoperative by the said lateral movements for holding said element against 25 longitudinal movements.
12. In a casement window, a window casing formed with an opening, a window sash hinged to said casing at a side thereof remote from said opening to turn between open and closed position, means tending to turn said sash away from and 30 opposing its return to its closed position, a flexible window operating element connected at one end to said sash and extending therefrom to the inner side of said window through said opening, a part detachably secured to said casing and formed with a keyhole slot in register with said sash opening through which said chain extends, and a lever member pivotally mounted on said part and comprising a sash locking hook portion extending through the lower portion of said slot through said opening and provided with a guideway for said chain at the inner side of the window which extends transversely to the axis of the pivotal mounting of said lever, said member 35 being adapted to be turned into and out of locking engagement with the sash, when the latter is in its closed position, by lateral movements given the portion of said chain extending away from said guideway at the inner side of the window, and being adapted by said movements to move a portion of said chain, between said guideway and sash, between positions respectively in the enlarged and narrow portions of said slot, the narrower portion of said slot being wide 40 enough to receive the body portions of the chain links but too narrow for the longitudinal movement therethrough of the connecting portions of adjacent links, said part being formed at its inner side with a recess adapted to form a seat 45 for the end of the chain link at the inner side of and connected to a link having its body portion received in the narrower portion of said slot.

HARRY E. CAMPBELL. 50
